(57) **CLAIM**

The ornamental design for a device for treating tissue, as shown and described.

DESCRIPTION

FIG. 1 is a perspective view of an open configuration of our new design for a device for treating tissue.

FIG. 2 is a front view thereof;

FIG. 3 is a first side view thereof;

FIG. 4 is a top view thereof;

FIG. 5 is a rear view of thereof;

FIG. 6 is a second side view thereof;

FIG. 7 is a bottom view thereof;

FIG. 8 is a perspective view of a closed configuration of our new design for a device for treating tissue.

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

(Continued)

In the drawings, the broken lines are shown for the purpose of illustrating a portion of the device for treating tissue and form no part of the claimed design.

1 Claim, 5 Drawing Sheets
